Application May 23, 1940, Serial No. 336,692
In Germany March 31, 1939

7 Claims. (Cl. 62—115)

This invention relates to a refrigerator equipped with a motor-driven refrigerating apparatus of the compression type.

To avoid the use of stuffing-boxes in such apparatus, the compressor and the driving motor are, as is well known, arranged in a common sealed housing. In such sealed motor-compressor units, the motor can only be provided with a squirrel-cage rotor. Accordingly, these hermetically-sealed units have hitherto been designed for alternating current only. It has already been proposed to supply the driving motor of such units with alternating current through a contact-type inverter connected to a direct-current supply circuit. This renders it possible to operate a sealed motor-compressor unit, designed for alternating current, also with direct current. The contact-type inverter may be combined with the refrigerating apparatus or cabinet so as to form a structural part thereof.

The invention aims at providing a particularly simple design of a contact-type inverter system for the above-mentioned purpose. According to the invention the contact-type inverter for feeding the A. C. motor-compressor unit from a D. C. supply network is driven by an electric motor which forms part of the refrigerating apparatus, preferably with the motor of a fan for supplying cooling air. Since in refrigerating apparatus of the compression type, having a sealed motor-compressor unit, a special fan is, as a rule, employed for carrying off the heat of condensation and the waste heat of the motor-compressor set, it is only necessary, according to the invention, to couple a contact-type inverter with the motor shaft of the fan, thus providing a very simple drive for the inverter. This drive is preferably so designed that the oscillating contact of the inverter is operated by the motor shaft through an eccentric drive.

According to another object of the invention, when employing contact-type inverters care should be taken to cool the contacts in an effective manner, since owing to the continual interruptions of the current considerable amounts of heat are liberated which may cause a deterioration of the contacts.

According to the invention cooling disks are therefore firmly secured to the contacts of the inverter having a sufficiently large cooling surface in contact with the surrounding air. This arrangement is preferably so designed that the cooling disks secured to the stationary contacts are bell-shaped and surround the cooling disks attached to the movable contacts. By thus designing the cooling disks, a powerful circulation

of air is obtained by the movements of the contacts, owing to the suction and pressure effects brought about by the cooling disks.

Other objects and features of the invention will be apparent from the following description of the embodiments illustrated diagrammatically in the accompanying drawing. Fig. 1 shows a circuit diagram and complete arrangement of a refrigerating apparatus of the compression type. Fig. 1A is a sectional view through the lower portion of a household refrigerator showing the relative positions of the elements disclosed in Fig. 1. Fig. 2 shows in detail the front view of the drive for a contact circuit breaker forming a D. C. to A. C. inverter for the purpose of the present invention. Fig. 2A is a side elevational view of Fig. 2. Fig. 3 illustrates the contacts of such an inverter provided with cooling disks as set forth in the foregoing, the disks being shown in cross section.

Referring to Fig. 1, the numeral 1 denotes the totally enclosed motor-compressor unit. 2 is a motor for operating a fan 41 serving to supply the refrigerating apparatus, in particular the condenser and the motor-compressor unit, with cooling air. 3 and 4 are the movable contact members of an inverting interrupter having stationary contacts 10, 11 and 12, 13 respectively. The movable contact members 3 and 4 each have a slot 9 in the upper end thereof which slots receive an eccentric pin 8 extending from disk 7 on the shaft 6 of motor 2. The numeral 5 denotes the customary thermostat disposed in heat contact with the evaporator. This thermostat connects and disconnects the fan motor 2 and opens and at the same time closes the circuit of the inverting contact circuit breaker serving to supply alternating current to the unit 1.

When in operation, the motor 2 is supplied with D. C. and controlled in response to the refrigerating temperature acting on the thermostat 5. The motor 2 operates fan 41, which fan supplies the unit 1 with cooling air and at the same time actuated the inverter with contacts 3 and 4 so as to supply the unit 1 with A. C. produced by the inverter from the D. C. supply current.

According to the embodiment of Fig. 2, the disk 7 carries an eccentric pin 8, which in turn penetrates slots 9 in the upper ends of contact members 3 and 4. As shaft 6 revolves the movable contacts oscillate back and forth so as to alternately engage counter contacts 10, 12 and 11, 13. This movement of contacts 3 and 4 will alternately close and open the circuit through the counter-contacts 10, 11 and 12, 13 respectively. By varying the amplitude of the contact

carrier (spring 3), the closure periods during which the unit 1 is inserted in the circuit may be adjusted in a known manner.

The inverter contacts of devices as shown in Figs. 1, 2 and 2A may be provided with cooling disks as exemplified by the embodiment of Fig. 3. In Fig. 3, the intermediate contact member of the inverting switch is denoted by 3a and the two outer contact members by 10a and 11a, corresponding, for instance, to the contact members 3 and 10, 11 respectively in Fig. 2. The members corresponding to contacts 4, 12 and 13 are not shown, but obviously may be of an identical construction as members 3a, 10a and 11a. Three cooling disks 24, 25 and 26, for instance of copper, are firmly secured to the three contact members 3a, 11a and 10a respectively. The disk 24, mounted on the intermediate member 3a, consists of a flat circular plate surrounded by a cylindrical portion, while the two outer disk members 25 and 26 are cup-shaped and substantially enclose the intermediate disk. The proximate rims of disks 25 and 26 are notched as at 25a and 26a respectively to permit oscillation of intermediate member 3a. Due to this design and arrangement of the cooling disks, the oscillatory movement of the contact arm 3a produces a powerful circulation of air, which aids in cooling the contacts, by the suction and pressure effects occurring alternately in the spaces 27 and 28. The outer surface of the arrangement is preferably exposed to cooling air blown over the contact arrangement in the direction indicated by the arrows, for instance, by means of the fan 2, 41 of the refrigerating apparatus. It is evident that the cooling disks 24, 25 and 26 shown in Fig. 3 may be employed on many types of oscillatory contact switches, irrespective of the manner in which the particular switch is operated.

What is claimed is:

1. A periodically-operating switching device for converting electric current, in particular for energizing a refrigerating A. C. apparatus from a D. C. source, comprising an intermediate contact and two outer contacts, means for oscillating said contacts relatively to one another so as to engage said intermediate contact alternately with one and the other outer contact, an inner disk-like cooling member secured to said intermediate contact, and two outer cooling members secured to said outer contacts respectively, said inner member and said outer members forming together two chambers of variable volume communicating with the surrounding air so as to produce an alternate flow of cooling air due to suction and compression in said chambers.

2. In a device according to claim 1, said inner cooling member comprising a disk of good heat-conductive material secured to said intermediate contact, and a cylindrical portion integral with said disk and surrounding said disk, and said outer cooling members being cup-shaped and arranged to substantially enclose said inner member.

3. In an electric refrigerator, the combination of a cold-producing refrigerant circulation system including a compressor, an A. C. motor for actuating said compressor, said motor and said compressor forming a sealed unit, current supply means for connecting said motor with a D. C. supply circuit, including an inverting contact device inserted between said motor and said current supply means, and means including a second electromotor for cooling the refrigerant circulat-

ing in said system, said second motor being connected with said supply means and actuating said inverting contact device.

4. In an electric refrigerating apparatus, the combination of a cold-producing refrigerant circulation system including a compressor, an A. C. motor for actuating said compressor, said motor and said compressor forming a sealed unit, an inverting contact device connected with said unit for energizing said motor with A. C., D. C. supply circuit means connected with said inverting device, temperature-responsive contact means for controlling said unit in response to the temperature in said refrigerating apparatus, said control means being connected between said inverting device and said D. C. supply means, and means including a second electromotor for cooling the refrigerant circulating in said system, said second motor being connected with said control means so as to be also controlled in response to said temperature, said inverting contact device being connected with said second motor to be actuated thereby also in response to said temperature.

5. In an electric refrigerating apparatus, the combination of a cold-producing refrigerant circulation system including a compressor, an A. C. motor for actuating said compressor, said motor and said compressor forming a sealed unit, current supply means for connecting said unit with a D. C. supply circuit, an inverting contact device inserted between said unit and said current supply means, and an electric fan for supplying said system with cooling air to cool the refrigerant in said system, said fan having an electromotor connected with said supply circuit, and said inverting contact device being connected with said fan motor to be actuated thereby.

6. In an electric refrigerating apparatus, the combination of a cold-producing refrigerant circulation system including a compressor, an A. C. motor for actuating said compressor, said motor and said compressor forming a sealed unit, current supply means for connecting said motor with a D. C. supply circuit, an inverting contact device inserted between said motor and said current supply means, and means including a second electromotor for cooling the refrigerant circulating in said system, said second motor being connected with said supply means and having a motor shaft provided with eccentric drive means, said inverting contact device having a movable contact member, and a follower connected with said movable contact member and engaging said drive means so that said movable contact member is oscillated by said second motor.

7. In an electric refrigerating apparatus, the combination of a cold-producing refrigerant circulation system including a compressor, an A. C. motor for actuating said compressor, said motor and said compressor forming a sealed unit, current supply means for connecting said motor with a D. C. supply circuit, an inverting contact device inserted between said motor and said current supply circuit, said device having contacts provided with cooling disks of heat-conductive material, and an electric fan for cooling the refrigerant in said system, said fan having an electric motor connected with said supply circuit, said inverting contact device being connected with said fan motor to be actuated thereby, and said cooling disks being arranged relative to said fan so as to be exposed to the cooling air supplied by said fan.

HANS SCHIRRMEISTER.
